CLAIM

The ornamental design for a computer display screen with an animated graphical user interface, as shown and described.

DESCRIPTION

1. Graphical user interface (display on computer screen)

1.1 is a front view of the first image of a computer display screen with an animated graphical user interface showing our new design;

1.2 is a second image thereof;

1.3 is a third image thereof;

1.4 is a fourth image thereof;

1.5 is a fifth image thereof;

1.6 is a sixth image thereof; and

1.7 is a seventh image thereof.

The outermost broken line, shown in the reproductions representing the computer display screen with an animated graphical user interface, form no part of the claimed design. The appearance of the animated graphical user interface sequentially transitions between the images shown in repro-

(Continued)

ductions 1.1 through 1.7. The process or period in which one image transitions to another image forms no part of the claimed design.
